BLOTTING DEVICE

Application filed February 17, 1930. Serial No. 429,135.

Our present invention has reference to a roller blotter for effectively and easily taking up surplus ink in writing letters and the like, and our object is the provision of a blotter having simple means whereby a blotting sheet may be replaced on the roller, a novel handle carrying hood or casing for the roller which sustains the handle above the desk surface so that the same may be readily grasped by the operator and novel means for removably journaling the roller in the hood.

To the attainment of the foregoing the invention consists in the improvement herein-after described and definitely claimed.

In the drawings:

Figure 1 is a side elevation of the improvement.

Figure 2 is a sectional view approximately on the line 2—2 of Figure 1.

Figure 3 is a perspective view to illustrate the manner in which the blotter sheet is arranged on or removed from the roller.

The roller 1 of the improvement may be of any desired material and the same has centrally fixed on one of its ends a short shaft 2. The shaft is in the nature of a pointed end that has its outer end rounded.

The second end of the roller is provided with a round socket in which there is received a tubular sleeve 3 that has its outer end closed. In the sleeve there is arranged a coil spring 4 that exerts a pressure upon the head 5 of the movable shaft 6 for the roller. The shaft passes through a central opening in the closed end of the sleeve.

The roller is peripherally formed with a longitudinal groove 7 which extends the entire length thereof and this groove is designed to receive therein the folded ends of a blotting sheet which is moved longitudinally over the roller when arranged thereon and moved off of the roller when removed therefrom.

The hood or casing for the roller is indicated by the numeral 8. The hood is in the nature of a substantially semi-cylindrical member that has closed sides 9 that has its rear formed with an outwardly arched skirt 10 that projects beyond the sides 9. On the

rear of the hood 8 there is centrally fixed a handle 11. The sides of the hood are formed with oppositely arranged outwardly bulged portions that afford inner sockets 12 and in these sockets the respective shafts 2 and 6 are received. As the major portion of the roller may be gripped by the hand of the operator it will be apparent that the said roller may be readily arranged in the hood and its shafts received in the sockets 12. The skirt 10 contacting with the desk surface will hold the handle elevated so that the same may be readily gripped by the operator. A large surface may be blotted by the absorbent paper by simply passing the roller thereover. The device is not only a useful implement for a desk but the construction thereof is ornamental.

It is thought that the foregoing description will fully set forth the construction and advantages of the improvement to those skilled in the art to which such invention relates but obviously we do not wish to be restricted to the precise details herein set forth and, therefore, hold ourselves entitled to make such changes therefrom as fairly fall within the scope of what we claim.

Having described the invention, we claim:

A blotting device comprising a handle carrying hood, that has its sides, at diametrically opposite points, depressed outwardly to provide concaved bearings, a blotter carrying roller having a fixed trunnion projecting from one of its ends and a spring influenced trunnion at its second end, said movable trunnion having an inner headed portion, a sleeve having an outer closed end let in the roller and receiving the headed end of the trunnion therein, both of said trunnions designed to be received in the bearings in the roller and the said roller being susceptible to removal from the hood when a pressure is exerted against the end thereof carrying the fixed trunnion to depress the movable spring influenced trunnion to permit of the roller being drawn out of the support and said trunnions having outer rounded ends whereby when the movable trunnion is depressed both of the trun-

nions are brought against the inner sides of the hood and the roller may be moved in the hood to again bring its trunnions in the bearings.

5 In testimony whereof we affix our signatures.

EDWIN G. HOFFSTADT.
ROBERT W. HOFFSTADT.
